UNITED STATES PATENT OFFICE.

FRANK E. LONAS, OF NEW YORK, N. Y.

INTERNAL-COMBUSTION ENGINE.

1,185,691.

Specification of Letters Patent.

Patented June 6, 1916.

Application filed September 23, 1913. Serial No. 791,282.

To all whom it may concern:

Be it known that I, FRANK E. LONAS, a citizen of the United States, residing at New York city, borough of Manhattan, in the county of New York, and State of New York, have invented certain new and useful Improvements in Internal-Combustion Engines, of which the following is a specification.

10 My invention relates to internal combustion engines and more particularly to the type wherein the admission of the charge and the exhaust of the burned gases are controlled by a sleeve valve in the head of the cylinder.

15 The main object of the invention is to provide an efficient water circulating system by which the valve or valves is or are placed between water jackets through which a continuous flow is maintained, and in multiple cylinder engines to provide means for passing the cooling water through the heads of the several cylinders in parallel.

20 Other objects of the invention are to provide an improved valve actuating mechanism, and a system by which the oil vapor from the crank case may be utilized for lubricating the valve.

25 These and other objects of the invention will be understood by reference to the accompanying drawings in which—

30 Figure 1 is a side elevation, partly in section, of a four-cylinder engine showing one embodiment of my invention; Fig. 2 a transverse vertical section on the plane of the line 2—2 of Fig. 1; Fig. 3 a part plan and part horizontal section; Fig. 4 a detail to show the manner of introducing the water into the water jacket; and Fig. 5 a detail 40 showing one of the liners in the valve-way.

Similar reference numerals indicate similar parts in the several views.

45 The invention is shown as embodied in a multiple cylinder engine of the four-stroke cycle type, in which the numeral 1 designates the upper part of the crank case to which the lower part 2 is secured. The upper part of the crank case, the cylinders 3 including their heads 4, and the outer casing 5 may be, and preferably are, made in a single casting to eliminate all joints. It is not essential, however, that this be done as the head may be cast separately and water passages provided from one to the other 50 through packed joints. The outer casing may be made in one casting and the cylinder heads and heads cast integrally and inserted into the casing and packed to give the same water circulation as herein described. The cover 6 is secured to the casing by any suitable means. Supported in bearings in the crank case is a crank shaft 7 to which the connecting rods 8 are secured. The pistons 9 may be of any usual design. They are shown as of the trunk type. As the several 55 cylinders and valves are similar in construction, it will only be necessary to refer to one of them.

60 Heretofore in engines of this type the internal head, which closes the upper end of the cylinder and between which and the cylinder wall the sleeve valve is placed, has been cast in a separate piece and fitted into the upper end of the engine cylinder. Owing to the exposure of the sleeve valve to 65 the high temperatures of the explosion chamber, considerable difficulty has been experienced in keeping the valve sufficiently cool to prevent burning of the lubricating oil and binding of the valve due to expansion of the metal and consequent distortion of the head or valve casing. To overcome these difficulties, so as to insure proper working of the valve, I have formed the head 4 integral with the body of the cylinder and with the outer casing 5, and have provided said head with a water jacket 10 extending circumferentially around the inner side thereof. As above stated the outer casing 70 may be made in one casting and the cylinders and heads cast integrally. The valve 11 is seated in a chamber or valve-way 12 formed in the head between the inner and outer walls thereof. Suitable ports 13 and 14 are formed in the sleeve valve for inlet 75 and exhaust, these ports communicating with ports in the cylinder head which open into the intake 15 and exhaust 16, respectively, at the times required for proper functioning. The valve-way 12 is thus surrounded both on the outside and inside with water jackets except the spaces occupied by the inlet and exhaust passages, so that the only part of the valve which is not water cooled is that which is at any moment opposite the ports in the cylinder head. To provide a continuous flow of water past the head and valve, the outer water jacket 18 is made to discharge through openings 19 into a chamber 20 in cover 6. 80

110

At the lower end of jacket 10, and below the valve-way 12, are openings 21 from the

outer jacket 18. The discharge from jacket 10 is through openings 22 in the upper part thereof into chamber 20 (see Fig. 1). The water supply to jacket 18 is from a passage 23 leading from the radiator (not shown), which passage, as shown in Fig. 4, discharges into jacket 18 at one end thereof, the water flowing upward in the latter and through inlets 21 into jacket 10 so as to completely surround the internal head or valve casing 4 on both sides of the valve 11, and discharging from both jackets 10 and 18 into chamber 20 in cover 6. By making the parts in a single casting absolutely water-tight and continuous jackets are formed. By inclosing all the cylinders in a single casing the inlet 23 will deliver water into jacket 18 for all of the cylinders, and the jacket 10 of each cylinder receives its supply from a common source, so that the water will pass around the internal heads in parallel and will be discharged from said heads through openings 22 into the common water compartment 20 covering all of the cylinders without the use of separate connecting pipes, or without passing from the head of one cylinder through the other cylinder heads in series. The water from chamber 20 is discharged therefrom through a pipe 24 to the radiator. The circulation may be effected by a pump if desired. The described arrangement, however, having a free inlet for the water at the bottom and free outlet at the top, is especially suitable for the thermosiphon system of cooling. The described system also presents the distinct advantage that there is a continuous flow of the water through the internal head to maintain an efficient cooling circulation on both sides of the sleeve valve. It also permits the draining of jacket 10 into the outer water jacket 18 without a siphon or other special means.

As shown in Figs. 1 and 2 the valve chamber 12 is made wider than is necessary to accommodate the valve, and liners 25 are provided, one on each side of the valve, these liners having apertures registering with the ports in the cylinder head. The liner on the inner side of the valve may, if desired, be cut away in the neighborhood of the port, as illustrated in Fig. 5, the object of this being to allow for expansion of the sleeve or the liner itself. Oil grooves may be cut as desired in the wall of chamber 12, or in the sleeve valve itself, or in the liners if such are used.

The valve may be actuated by any suitable mechanism requisite for the four-cycle motion, the engine being of that type, as for example, by a train of gears or by silent chains 26 and 27 (see Fig. 1) running over suitable sprocket wheels, the shafts of which actuate cranks to which the connecting rods of the valve are attached. In the present construction I have provided a novel form

of connection between the crank driving mechanism and the valve comprising a cross head in the form of a yoke or ring 28 having trunnions 29 slidably supported in bearing sleeves 30, the latter being carried by cranks 31 and 32. The cranks are on shafts driven by the chains 26 and 27, the connections between the driven shafts being so adjusted as to drive crank 31 at one half engine speed and crank 32 at engine speed, as is well understood in the art. Rods 33 connect the cross head 28 with the sleeve valve through ears or lugs 34 projecting laterally therefrom, as shown in Figs. 1 and 3. The connecting rods 33 are in a plane substantially at right angles to the vertical plane of the trunnions 29 and pass through chambers 35 formed by walls 36 to cut off said chambers from the water jacket 18. No novelty is claimed by me for the mechanism for driving the cranks 31 and 32, but by placing said cranks on diametrically opposite sides of ring 28, and by connecting the valve to the ring in the manner described, the forces acting on the valve are better balanced and the tendency to binding and vibration of the mechanism between the cranks and the valve is reduced to a minimum. If there should be any tendency to bind it is overcome by the capability of the cross head to rock in its bearings 30.

The chambers 35 are utilized by me to effect the lubrication of the valve in the following manner. The shaft bearings are lubricated in the usual way by forced lubrication through pipe 37 and connections 38 to the bearings, and as is well known, the lubricant is thrown off by the shaft resulting in filling the crank case with a vapor or mist of oil which, heretofore, has been permitted to escape through breathers on the crank case. In order that the oil vapor may be utilized for the purpose stated, I dispense with the crank case breathers and permit the vapor to escape through the chambers 35, which open into the crank case as indicated by the dotted lines in Fig. 2. These chambers terminate at their upper ends in a breather 39. The compression of the oil vapor in the crank case, due to the reciprocation of the pistons, forces the vapor upwardly through the chambers 35, surrounding the valve rods 33, and into the space into which the valve is moved in its reciprocations. The movements of the valve assist in drawing in the vapor, thereby lubricating its surface. The breather is provided with baffles 40 to trap and prevent the escape of oil particles carried by the vapor.

What I claim and desire to secure by Letters Patent of the United States is:—

1. In an internal combustion engine, a cylinder with inlet and exhaust ports and having a head, a sleeve valve seated in a chamber in said head, water jackets on both

sides of the valve chamber, and means for causing a continuous flow of water in the same direction through the jackets.

2. In an internal combustion engine, a cylinder with inlet and exhaust ports and having a head, a valve governing said ports, an outer water jacket section surrounding the cylinder and head, a water jacket section around the inner side of the head and having an opening into the outer jacket, and a cover for the cylinder having a compartment into which the water discharges.

3. In an internal combustion engine, a cylinder with inlet and exhaust ports and having a head, a valve governing said ports, and water jacket sections made integral with the cylinder and head and extending around the cylinder head on both sides thereof and communicating with each other, and a common discharge for said jackets.

4. In an internal combustion engine a cylinder having inlet and exhaust ports, a valve or valves governing said ports, and water jackets both sides the valve or valves communicating with each other, and an independent discharge for each of said jackets.

5. In an internal combustion engine, a cylinder having a ported valve chamber formed between water jackets communicating with each other at the lower part thereof, each jacket provided with an independent outlet.

6. In an internal combustion engine, a cylinder with inlet and exhaust ports, and having a head, a sleeve valve seated in a chamber in said head, outer and inner water jackets around said head, said inner jacket having openings leading from the outer jacket, and both of said jackets having outlets at the upper parts thereof to provide for a continuous flow of water in the same direction on both sides of the valve.

7. In an internal combustion engine a cylinder with inlet and exhaust ports, and having a head, a sleeve valve seated in a chamber in said head, outer and inner water jackets around said head, a chambered cover for the cylinder head and water jackets, said water jackets communicating with each other through openings leading into the lower part of the inner jacket, and each of said jackets having a discharge opening into the chamber in said cover.

8. In an internal combustion engine, a cylinder having a head integral therewith, said head including a water jacket on the inner side thereof, an outer water jacket surrounding the cylinder and head and communicating with the inner water jacket near the lower part thereof, both of said jackets having a discharge outlet at the upper part thereof, and a valve seated in a chamber in said head between the water jackets.

9. In an internal combustion engine, a cylinder having a head with inlet and ex-

haust ports, said cylinder and head made integral with each other and the latter having a water jacket on the inner side thereof and integral therewith, an outer water jacket communicating with the inner jacket, a valve in a chamber in said head between the water jackets and surrounded thereby and a separate outlet for each of said water jackets at the upper part thereof.

10. In an internal combustion engine, a cylinder having a head with inlet and exhaust ports, said cylinder and head made integral with each other and the latter having a water jacket on the inner side thereof and integral therewith, an outer water jacket communicating with the inner jacket, a chambered cover for said head and jackets the latter having discharge openings into the cover, and a valve in chamber in said head between the water jackets and surrounded thereby.

11. In a multi-cylinder internal combustion engine, a casing forming a water jacket surrounding the cylinders and common to all of them, a water inlet to the jacket, a water jacket on the inner side of each cylinder head, said inner jackets communicating with the outer jacket, a common outlet for all of said jackets, and a valve in a chamber in each of said heads between the water jackets and surrounded thereby.

12. In a multi-cylinder internal combustion engine, a casing forming a water jacket surrounding the cylinders and common to all of them, a water inlet to the jacket, a water jacket on the inner side of each cylinder, said inner jackets communicating with the outer jacket, a common outlet for all of said jackets, valve chambers formed between said outer and inner water jackets, and valves in said chambers.

13. In a multi-cylinder internal combustion engine, a casing forming a water jacket surrounding the cylinders and common to all of them, a water inlet to the jacket, a water jacket on the inner side of each cylinder head, said inner jackets communicating with the outer jacket, a chambered cover common to all of the cylinders and having openings to permit of the discharge of all of the jackets into the chamber, an outlet for said chamber, and a valve in a chamber in each of said heads between the water jackets and surrounded thereby.

14. In an internal combustion engine, a cylinder having a head with inlet and exhaust ports, said head having communicating water jackets on the inner and outer sides thereof, and a valve in a chamber in said head between the water jackets and surrounded thereby, said inner jacket having an inlet at its lower end and an outlet at its upper end.

15. In an internal combustion engine, a cylinder having a head with inlet and ex-

4

haust ports, a valve or valves governing said ports, an outer water jacket section surrounding the cylinder head, a water jacket section around the inner side of said head, 5 and having an opening or openings therefor at both bottom and top of said inner water jacket for the passage of water.

16. An internal combustion engine having a cylinder and a valve in the head thereof, and a water cooling system comprising jackets on the inner and outer sides of the valve, and means for causing a continuous flow of water in the same direction through said jackets.

15 17. An internal combustion engine having a cylinder and a valve in the head thereof, and a water cooling system comprising jackets on the inner and outer sides of the valve, means for causing a continuous flow 20 of water in the same direction through said jackets, and a common water discharge for said jackets.

18. An internal combustion engine having cylinders each provided with a head 25 having an explosion chamber, a valve chamber and inlet and exhaust ports, one or more valves controlling said ports, a water-cooling system comprising a main jacket for the engine, said jacket being divided at or near the lower end of said valve chamber whereby water is supplied to each side thereof, and outlets for the water at the top of said valve chamber.

19. An internal combustion engine having cylinders provided with heads having

explosion chambers and inlet and exhaust ports, valves controlling said ports, chambers for said valve and a water cooling system comprising a jacket or casing having division walls whereby the water is caused 40 to flow in parallel columns in a continuous direction longitudinally of the cylinders and heads and inside and outside of the chambers in which said valves are placed, and a discharge outlet for the water, said 45 division walls permitting the water to be drained from the jackets.

20. In an internal combustion engine, an annular valve chamber formed between a cylinder having a water-cooled head and surrounded by a sleeve valve and an outer water jacket casing, the jacket of the head being provided with an outlet in its upper end and being open at its lower circumference to receive an upward flow of water 55 from the main outer water jacket.

21. A cylinder and head construction for internal combustion engines comprising a valve chamber and a valve therein, said chamber being closed at the bottom, two 60 water-cooled jackets between which said valve chamber is located, and a chambered cover into which said jackets open.

In testimony whereof I have hereunto signed my name in the presence of two sub- 65 scribing witnesses.

FRANK E. LONAS.

Witnesses:

M. E. McNINCH,
CHARLES S. JONES.

haust ports, a valve or valves governing said ports, an outer water jacket section surrounding the cylinder head, a water jacket section around the inner side of said head, and having an opening or openings therefor at both bottom and top of said inner water jacket for the passage of water.

16. An internal combustion engine having a cylinder and a valve in the head thereof, and a water cooling system comprising jackets on the inner and outer sides of the valve, and means for causing a continuous flow of water in the same direction through said jackets.

17. An internal combustion engine having a cylinder and a valve in the head thereof, and a water cooling system comprising jackets on the inner and outer sides of the valve, means for causing a continuous flow of water in the same direction through said jackets, and a common water discharge for said jackets.

18. An internal combustion engine having cylinders each provided with a head having an explosion chamber, a valve chamber and inlet and exhaust ports, one or more valves controlling said ports, a water-cooling system comprising a main jacket for the engine, said jacket being divided at or near the lower end of said valve chamber whereby water is supplied to each side thereof, and outlets for the water at the top of said valve chamber.

19. An internal combustion engine having cylinders provided with heads having

explosion chambers and inlet and exhaust ports, valves controlling said ports, chambers for said valve and a water cooling system comprising a jacket or casing having division walls whereby the water is caused to flow in parallel columns in a continuous direction longitudinally of the cylinders and heads and inside and outside of the chambers in which said valves are placed, and a discharge outlet for the water, said division walls permitting the water to be drained from the jackets.

20. In an internal combustion engine an annular valve chamber formed between a cylinder having a water-cooled head and surrounded by a sleeve valve and an outer water jacket casing, the jacket of the head being provided with an outlet in its upper end and being open at its lower circumference to receive an upward flow of water from the main outer water jacket.

21. A cylinder and head construction for internal combustion engines comprising a valve chamber and a valve therein, said chamber being closed at the bottom, two water-cooled jackets between which said valve chamber is located, and a chambered cover into which said jackets open.

In testimony whereof I have hereunto signed my name in the presence of two subscribing witnesses.
